UNITED STATES PATENT OFFICE.

AMANDUS BUTCHER, OF ALBANY, OREGON.

EXTENSION STEP-LADDER.

1,233,975.

Specification of Letters Patent. Patented July 17, 1917.

Application filed February 29, 1916. Serial No. 81,205.

To all whom it may concern:

Be it known that I, AMANDUS BUTCHER, a citizen of the United States, residing at Albany, in the county of Linn and State of Oregon, have invented new and useful Improvements in Extension Step-Ladders, of which the following is a specification.

This invention relates to improvements in step ladders, and has particular reference to 10 the foldable type.

The primary object of the invention resides in the provision of a device of this character including an auxiliary extensible section adapted to be automatically engaged 15 and held between the main section and support therefor in adjusted position.

In carrying out my invention I provide the upper step of the main section with a fixed portion and a relatively movable portion, the latter being adapted for use when the auxiliary section of the ladder is dispensed with, and serving to prevent collapsing of the ladder should one of the braces 20 thereof be broken.

With these and other objects in view, which will appear as the nature of the invention is better understood from the following description, the invention resides in the construction, combination and arrangement of 25 parts as outlined in the appended claims.

In the drawings forming part of this specification, like numerals of reference indicate similar parts in the several views and wherein:—

Figure 1 is a front elevation of the device showing the auxiliary section in extended position.

Fig. 2 is a side elevation thereof.

Fig. 3 is a view of the ladder folded.

Fig. 4 is a sectional view on line 4—4 of Fig. 2.

Fig. 5 is an enlarged detail sectional view of the ladder with the auxiliary section removed.

Referring more particularly to the drawings A indicates a ladder of the usual well known construction, including a main section 10 and a prop 11 therefor. The prop may be pivotally associated with the main section 45 in any suitable manner, preferably by means of the spaced parallel strips 12, which latter are terminally secured to the opposite sides

of the ladder and extend an appreciable distance toward the rear thereof. The strips 12 have their corresponding ends offset inwardly as at 13, and connected by means of a brace rod 14, the latter serving as a pivot for the prop 11. By reason of this construction the prop 11 is spaced from the main section 10 a sufficient distance to accommodate the slidable section 15, which is 55 slidably mounted between the said parts as shown. It will now be noted that by the provision of the offset portions 13 of the strips 12, a flange 16 is provided, which 60 latter cooperates with the main body portion of the strips 12 and the main section 10 to guide the auxiliary section in its adjustment. The auxiliary section is further guided in its adjustment by a substantially 65 U-shaped yoke member 17 having its terminals secured in any suitable manner to the side portions of the main section 10 at a point in its length.

The upper step of the main section 10 consists of a fixed portion 18 and hinged step 19. Secured to the outer longitudinal edges of the prop 11 are spaced blocks 20, each of which has secured thereto one leaf 21 of a hinge, the cooperating leaf 22 being 80 fixed to the upper surface of the hinged step 19. As shown in Fig. 5 the hinged step 19 is adapted to rest upon the blocks 20 and the prop 11 in operative position, and provides with the fixed portion 18 a relatively broad 85 step. By reason of the specific disposition of the hinged step 19 with respect to the prop 11, coupled with the fact that the adjacent edges of the fixed portion 18 and the hinged step 19 are correspondingly beveled, the prop 90 is held from slipping or moving away from the main section 10 should for any reason one of the braces for the ladder become broken. These tie braces may be of any suitable construction, and as herein shown consist of a 95 pair of pivotally connected flat strips of metal, which are terminally connected with the main section 10 and the prop 11 respectively. One of the strips has a tongue 23 formed thereon for engagement with the upper edge of the adjacent strip to hold 100 these parts in alinement when the prop 11 is extended to a position for use.

It is to be understood however that when

the hinged step 19 of the step is in the position shown in Fig. 5, the auxiliary section 15 is dispensed with, and when use of the latter is desired, the hinged step 19 is 5 swung upon its hinge to an inoperative position against the prop 11 and blocks 20 as shown. In practice when use of the auxiliary section is desired, the latter is elevated the required distance, with the prop 10 11 in parallelism with the main section 10, and subsequent to this adjustment the prop 11 is extended whereby the upper edge thereof is moved beneath the adjacent step of the auxiliary section thereby clamping 15 the ladder between the prop 11 and the fixed portion 18 of the uppermost step of the main portion 10. The steps of both the main section 10 and the auxiliary section 15 are equidistantly spaced and similarly inclined so as 20 to lie in the same horizontal plane irrespective of the adjusted position of the auxiliary section 15. It is to be understood that the clamping of the auxiliary section is automatic, thereby permitting the parts to be 25 expeditiously adjusted for use. It will be further noted that by reason of the construction hereinabove described, use of all metal fastenings such as hooks, dogs and the like essential in the construction of ladders now 30 in use are wholly dispensed with, and the parts more effectively held in adjusted position, thereby insuring safety in the use of the device.

It is believed that from the foregoing description the nature and advantages of the invention will be readily apparent without requiring a more extended explanation and therefore the same has been omitted. However I desire to have it understood that what 35 40 is herein shown and described is merely illustrative of one embodiment of the invention, to which I do not limit myself, as various changes in the construction, combination and arrangement of parts may be

resorted to when desired as fall within the scope of the appended claims.

What is claimed is:—

1. A step ladder comprising a main section, a swingingly mounted prop therefor, an auxiliary extensible section mounted for sliding adjustment between the main section and said prop, said extensible section being adjustable when the main section and prop are arranged in parallelism, and the upper extremity of said prop engaging beneath one of the steps of the extensible section, when the prop is extended to hold the extensible section in its adjusted position.

2. A step ladder comprising a main section, a swingingly mounted prop therefor, an auxiliary extensible section slidably fitted between the main section and said prop, the upper end of said prop engaging beneath the step of the auxiliary section to support the ladder in adjusted position, and the steps of said auxiliary section being disposed to align with the steps of the main section when so adjusted.

3. A step ladder comprising a main section, a pivotally mounted prop therefor, a hinged step carried by the prop and adapted to align with the uppermost step of the main section when in use, an auxiliary extensible section slidably fitted between the main section and said prop, said hinged step being adapted to fold outwardly against the prop when the auxiliary extension is employed, and the upper extremity of said prop engaging beneath the step of the auxiliary section to hold the latter fixed in its adjusted position.

In testimony whereof I affix my signature in presence of two witnesses.

AMANDUS BUTCHER.
